BUILDING CONSTRUCTIONS

Charles J. Fox, Ellicottville, N. Y.

Application September 14, 1935, Serial No. 40,648

3 Claims. (Cl. 189—88)

This invention relates to new and useful improvements in building constructions.

A primary object of the invention is to provide a portable building structure which may be readily assembled and disassembled from parts completely manufactured at the factory.

A further important improvement provided by this invention is to construct a building frame from channel members which are properly interconnected to provide the necessary studding, base support, and the like.

A further important object of the invention is to provide means for securing finishing sheets or panels to the inner and outer faces of the studs.

Other objects and advantages of the invention will be apparent during the course of the following description:

In the accompanying drawings forming a part of the specification and in which like numerals are employed to designate like parts throughout the same,

Figure 1 is a perspective view taken on the inner side of a wall structure embodying this invention,

Fig. 2 is a transverse sectional view of the structure shown in Fig. 1,

Fig. 3 is a similar view to Fig. 2 but discloses a different arrangement of the inner and outer locking devices for the finishing sheets or panels,

Fig. 4 is an exploded view of the elements which constitute the securing device for the outside finishing sheets or panels, and

Fig. 5 is an exploded view of the elements which cooperate to form the securing device for the interior finishing sheets or panels.

In the drawings, wherein for the purpose of illustration is shown the preferred embodiment of this invention, the numeral 6 designates the base member of the frame structure for the building embodying this invention. This base member is of channel formation and is constructed from a suitable gauge sheet metal. At suitable intervals, the channel base member 6 is intended to have mounted therein, and suitably secured thereto, studs which are formed of two channel members 7 and 8 adapted to be arranged back to back. The backs or webs of these channels 7 and 8 may be spot-welded together at as many different points as desired, or bolts may be employed for that purpose. With the channel members 7 and 8 connected in the manner illustrated, the flanges 9 and 10 will form the inner face of the studding while the flanges 11 and 12 will form the outer face of the studding. Figs. 1, 2, and 3 disclose this studding construction.

The exterior of the building is intended to be formed by a suitable number of metal sheets or panels. These sheets or panels may have any desired dimensions and are intended to be provided with a porcelain enamel finish. These exterior sheets or panels are intended to be secured to the studding so that their adjacent edges are offset with respect to the seam or joint formed between the connected webs or backs of the channel members which form the studding. In Figs. 10 5 and 12, the exterior sheets or panels 13 and 14 are properly associated with the studding.

Fig. 4 discloses in detail the two elements or strips which are employed for securing the exterior panels 13 and 14 in place and for closing 15 the seam or gap between the adjacent edges of these panels. A channel-shaped key member 15 is connected by spot-welding, screws, or the like to one flange of one of the channel studding members. In the present illustration of the invention, the back 16 of the key 15 is secured to the flange 11 of the channel member 7. The sides 17 of this key 15 have formed on their outer edges, laterally extending flanges 18. These flanges are arranged at an acute angle with respect to the sides 17. The extreme edges of these lateral flanges, therefore, point inwardly toward the flange 11 of the studding. It will be noted that the exterior sheets or panels 13 and 14 have their adjacent edges underlying these lateral 20 flanges or wings 18 of the key strip 15. A cover or cap 19 of channel formation is provided to house the key 15 and complete the locking device. This cover or cap 19 is provided with inwardly directed flanges 20 which are carried by the side 25 walls of the channel. With the exterior sheets or panels 13 and 14 positioned as shown in Figs. 1, to 3 inclusive, with their adjacent edges underlying the wings or flanges 18 of the key strip, the cap or cover strip 19 may be telescoped or 30 slipped longitudinally over the key strip. The inturned flanges 20 of the cover or cap then will flatly engage the sheets or panels and will be clamped thereagainst by the flanges or wings 35 18 of the key. The positioning of the cap or cover 19 on the key 15 is intended to spring the flanges or wings 18 outwardly away from the studding, to a desired extent, for producing a tight fit between the flanges 20 of the cap and the sheets or panels. The exposed surfaces of the 40 cap or cover 19 should be provided with a porcelain enamel finish.

The interior finishing sheets or panels 21 and 22 are intended to be secured to the inner face of the studding by the elements disclosed in Fig. 55

5. These elements include a channel-shaped key strip 23 which is spot-welded to one of the flanges of one of the channel members 7 and 8. Screws or bolts also may be employed for connecting this key to the studding flange. In Fig. 2, the inner key 23 is disclosed as being secured to the second flange of the same channel 7 which carries the key of the outer locking device. In Fig. 3, the inner key 23 is disclosed as being secured to a flange on the second channel 8 or so that the inner and outer securing devices will be staggered with respect to each other. Either one of these arrangements of the locking devices may be adopted in accordance with the desires of the manufacturer. This key strip 23 has formed on the free edges of its side walls the two inwardly directed flanges 24. This key 23 forms a trough for the reception of the rectangularly shaped head 25 of the securing bolt 26. Any desired number of these bolts may be provided. A channel-shaped cover strip 27 is adapted to be associated with the key 23. This cover strip 27 includes a back 28 having apertures 29 formed therein at desired intervals. Side walls of the cover 27 have inwardly directed flanges 30 formed thereon. Each bolt 26 is provided with a nut 31, as illustrated in Figs. 1 to 3 inclusive.

In securing the inner sheets or panels 21 and 22 to the inner face of the studding, the said sheets or panels are positioned with their adjacent edges arranged on opposite sides of the key 23. A suitable number of bolts 26 then are arranged with their heads 25 positioned within the trough of the key 23. The cover 27 is then positioned to overlie the key and the adjacent edges of the sheets or panels with the bolts 26 passing through the apertures 29. By positioning the caps 31 and tightening the same upon the bolts 26, the cover 27 is firmly secured in place and clamps the sheets or panels 21 and 22 to the inner face of the studding. The inner sheets or panels are intended to have their surfaces finished with porcelain enamel. The exposed surfaces of the cover 27 also are intended to be provided with a porcelain enamel coating.

It is to be understood that horizontally extending studs may be provided wherever desired and they will take the same form as the vertical studding disclosed herein. Similar securing devices may be mounted on such horizontal frame members.

It is to be understood that the form of this invention herein disclosed and described is to be

taken as a preferred example of the same, and that various changes may be made in the shape, size and arrangement of parts without departing from the spirit of the invention or the scope of the subjoined claims.

5

Having thus described the invention, I claim:

1. A building structure comprising a frame member formed of two channel elements connected back to back, and means for detachably fastening two panels to one flanged face of the 10 member, said means comprising a key strip of channel formation having its back secured to a flange of only one of the two channel elements and having a transversely extending flange carried by each side wall thereof, a cover strip to 15 overlie the key strip and having inwardly directed flanges terminating laterally outwardly of the key strip to clamp the panels against the frame member, and means engaging the side flanges of the key strip to hold the cover strip in 20 place.

2. A building structure comprising a frame member formed of two channel elements connected back to back, and means for detachably fastening two panels to one flanged face of the 25 member, said means comprising a key strip of channel formation having its back secured to a flange of only one of the two channel elements and having a transversely inwardly extending flange carried by each side wall thereof, a channel-shaped cover strip to overlie the key strip, and means having a head underlying the side flanges of the key strip to hold the cover strip in place.

3. A building structure comprising a skeleton 35 frame including an H-shaped studding member, a key strip fastened to said studding member and extending longitudinally thereof, said key strip comprising a back, side walls, and flanges extending laterally in opposite directions from said side walls, said flanges being inclined toward said studding member, panel elements engaging said studding member and having portions underlying said opposite flanges of said key strip, and a cover strip enclosing said 40 flanges and having portions thereof underlying said flanges, said flanges of said key strip being adapted to be sprung outwardly slightly when said cover strip is placed in assembled position, whereby said flanges tend to press the underlying 45 portions of said cover strip and said panels toward said studding member.

CHARLES J. FOX.
